UNITED STATES PATENT OFFICE.

MICHAEL J. RILEY, OF EAST CLEVELAND, OHIO.

BOLT MACHINE.

Application filed August 2, 1920. Serial No. 400,705.

To all whom it may concern:

Be it known that I, MICHAEL J. RILEY, a citizen of the United States, residing at East Cleveland, Ohio, have invented certain new and useful Improvements in Bolt Machines, of which the following is a specification.

The invention relates particularly to a machine which will automatically cut screw threads on the shanks of headed blanks fed to it. It also contemplates pointing the blanks when desirable or necessary.

In general the invention includes a hopper into which the blanks may be thrown promiscuously. The blanks may be assorted and arranged and passed from the hopper to a chute at the end of which they may be received by suitable mechanism for delivering them into position to be grasped and held while a cutting device may operate on them.

One purpose of the invention is to provide means for conveniently retaining the blanks in the chute in association with mechanism for releasing the maintaining means and removing the blanks.

A purpose is to pass the blanks in a substantially upright position down the chute and deliver them to receiving means which will turn the blanks to a substantially horizontal position so that they may be horizontal when operated on by the cutters.

Another purpose of the invention is to transfer the blanks from the chute into position to be grasped by movable jaws in such a way that the jaws may grasp either the head or shank of the blank at a predetermined point.

Another purpose of the invention is to provide the clamping jaws with a relieving mechanism so that a positive drive for the jaws may function properly and at the same time compensate for unusual blanks or those irregularly placed.

A further purpose of the invention is to provide means for properly positioning the blanks in the gripping jaws. These means may be adjustable and may move with or be operated by the jaws.

In one aspect the invention includes picker fingers intermediate the chute and the gripping jaws to position the blanks to be properly grasped by the jaws. These fingers may be adjustable toward and from each other

and they may be adjustable as a unit in the member which supports them. They may be resiliently mounted so as to conveniently grasp and hold blanks of varying sizes and the fingers as a unit may be resiliently mounted so that they may be free to move to allow the blank to be properly grasped by the jaws.

In another aspect the invention contemplates a spindle carrying the thread cutting die head or a bolt pointer head which may be in axial alignment with the blank in the gripping jaws and which may be rotated and reciprocated toward and from the blank. The spindle may be carried in a head which may be adjustable along the bed of the machine toward and from the gripping jaws so as to provide for operation upon blanks of various lengths. The spindle rotating and reciprocating mechanisms may likewise be adjustable and may include a gear and cams all being arranged so that the spindle, cams and gear may be adjusted toward or from the blank holder.

Another feature of the invention includes a yielding mechanism in the spindle reciprocating device which may allow the positively driven reciprocating mechanism to operate normally while allowing the thrust of the spindle to be relieved if an emergency requires. This may be associated with a cam for initiating the movement of the thread cutting die head which may allow it to be drawn onto the blank beyond the throw of the cam for the rest of the cutting travel.

A further purpose of the invention is to provide a single driving mechanism which may be geared to rotate the spindle on one hand and on the other hand may drive a cam shaft through gearing including a worm. The cam shaft may carry cams for operating the various elements of the machine including the reciprocatory movements of the spindle, the gripping jaws, the picker fingers and the means for receiving the blanks from the chute.

The invention in another aspect contemplates means which may be operated by the cam shaft to operate cutter releasing mechanism in the cutter head and so limit the amount of thread cut irrespective of the amplitude of the reciprocatory movements of the spindle. Means may also be provided for automatically returning the cutters in

the head to cutting position toward the end of the movement by which the cutter head is retracted from the blank.

Other purposes, objects and aspects of the invention will appear from the following description and will be more definitely pointed out in the appended claims.

For the purpose of fully describing the nature and advantages of the invention a specific embodiment thereof will be described as illustrated in the accompanying drawings. It should be understood, however, that the invention is capable of various modifications and, therefore, it is not limited to the particular structure illustrated.

In the accompanying drawings Figure 1 is a plan view of the machine; Fig. 2 is a front elevation; Fig. 3 is an end elevation from the right of Fig. 1; Fig. 4 is an end elevation from the left of Fig. 1; Fig. 5 is a transverse vertical section through the gripping jaws for holding the blank; Fig. 6 is a detail elevation of the device for relieving the jaw movement; Fig. 7 is a transverse vertical section through the same; Fig. 8 is a detail elevation of the device for receiving the blank from the chute and its operating mechanism; Fig. 9 is a fragmentary plan of the end of the chute and the device for receiving the blank therefrom; Fig. 10 is a front elevation of the device for receiving the blank from the chute; Fig. 11 is a side elevation of the cam for operating the device for receiving the blanks from the chute; Fig. 12 is a plan view of said cam; Fig. 13 is a developed view of said cam; Fig. 14 is a transverse vertical section of the machine through the spindle carrying the cutter head; Fig. 15 is a side elevation of the cams for reciprocating the spindle; Fig. 16 is a developed view of one of said cams; Fig. 17 is a transverse vertical section showing the device for opening the cutter head and its cam; Fig. 18 is a vertical section through a part of the mechanism for driving the cam shaft; Fig. 19 is a fragmentary plan view of the device for properly positioning the blanks in the gripping jaws; Fig. 20 is a fragmentary plan view similar to Fig. 19 showing the device in retracted position; Fig. 21 is a fragmentary plan view similar to Fig. 19 showing the device in another adjustment; Fig. 22 is an elevation of one form of gripping jaws; Fig. 23 is an elevation of another form of gripping jaws; and Fig. 24 is a fragmentary side elevation of the end of the chute and the device for receiving blanks therefrom showing an optional arrangement.

The machine comprises a bed 1 on which is supported a drive shaft 2 provided with a drive pulley 3. The drive shaft carries a gear 4 which engages a gear 5 on a jack shaft 6. The jack shaft 6 also carries a gear 7 which engages a gear 8 on a second jack shaft 9. At its inner end the jack

shaft 9 carries a bevel gear 10 which engages a bevel gear 11 on a transverse shaft 12 which carries a worm 13 engaging a worm gear 14 on a cam shaft 15. This train of gears provides for a reduction of speed between the drive shaft and the cam shaft and their relative speeds may be altered by replacing one or more of the gears.

The frame of the machine supports a hopper 16 into which headed blanks may be thrown promiscuously. The hopper 16 is provided with a chopper 17 of a well known form to properly arrange the blanks. A roller 18 is carried by an arm 19 mounted on a transverse shaft 20 which carries a bevel gear 21 engaging a bevel gear 22 on a shaft 23 which also carries a sprocket 24 driven by a chain 25 passing over a sprocket 26 on the cam shaft 15. As the arm 19 rotates it causes the roller 18 to wipe the arc shaped bottom 27 of the chopper 17, thereby causing it to rise and fall in the hopper to arrange the blanks in the well known way. A spring 23^a on the shaft 23 allows the sprocket 24 to rotate on the shaft to relieve the mechanism should the chopper stick or be locked by misplaced blanks. The blanks are arranged in the chopper so as to hang by their heads and at the upper end of the chopper stroke those so arranged slide by gravity into the chute 28, which, as shown, is provided with a guard 29 to keep the blanks in order.

At its lower or outlet end the chute is provided at each side with a lock 30, which may be forked, pivoted at 31 on the chute side and forced by a spring 32 into the mouth of the chute so as to prevent blanks from dropping out. (See Fig. 9.) The outer sides of the locks 30 are beveled toward their meeting point and each lock is provided with a set screw 33.

A transverse shaft 34 carried in bearings 35 on the bed of the machine carries at one end a transfer carrier arm 36. At its other end the shaft 34 carries a pinion 37 which is engaged by a toothed arc 38 on one end of an arm 39 pivoted on the bed at 40. At its other end the arm 39 carries a roller 41 adapted to be engaged by a cam 42 mounted on the cam shaft 15. The cam 42 is shown in detail in Figs. 11, 12 and 13. A spring 43 mounted on the bed of the machine bears against the arm 39 and tends to hold the apparatus in position to cause the transfer arm 36 to be in a horizontal position. A stop 34^a adjustable on the shaft 34 engages a web 35^a in the bed and limits the movement of the transfer carrier arm 36 as caused by the spring 43 to such as will cause the arm 36 to be substantially horizontal. As its rotates the cam 42 engages the roller 41 so as to cause the toothed arc 38 to rotate the pinion 37 and swing the transfer

carrier arm 36 through about 60° upward from the horizontal to the outlet of the chute 28. The face of the transfer carrier arm 36 is beveled as at 45 so that as it approaches 5 the locks 30 the bevels 45 engage the set screws 33 in the locks 30 and so force them to separate against the pressure of the springs 32. The set screws 33 may be adjusted to accommodate the transfer carrier arm and properly 10 cooperate therewith and so as to cause the locks 30 to separate sufficiently to allow a blank to pass out between them. This allows the lowermost blank in the chute to drop by gravity into the cavity 46 on the transfer 15 carrier arm 36. The transfer carrier arm weighted down by the blank then returns under pressure of the spring 43 to its horizontal position as allowed by the stop 35^a and the cam 42, carrying the blank with it. 20 The locks 30 return under pressure of the springs 32 to the position to hold the remaining blanks in the chute as soon as the beveled faces 45 leave the set screws 33.

A longitudinal shaft 47 mounted in the 25 bed of the machine carries a rearwardly extending arm 48 on which is a roller 49 engaged by a cam 50 on the cam shaft 15. The shaft 47 also carries a forwardly extending arm 51 provided at its forward end with a fork 52 in which is a transverse pin 53. A coil spring 51^a fastened to the bed 1 and the arm 51 tends to hold the forward end of the arm substantially horizontal and also holds the roller 49 against the edge of the cam 50. 30 Pivoted on the pin 53 are jaws 54 and 55 acting as picker fingers for the blank. At their tips the jaws or fingers 54 and 55 may be forked as shown in Fig. 2. The jaw 55 carries a set screw 56 by which the distance 40 between the jaws may be regulated. A lug 57 depending from the fork 52 carries a set screw 58 which adjusts the position of the jaw 54 and consequently of the picker fingers as a unit with relation to the arm 51. Ex- 45 tending upwardly and beyond the pivot pin 53 the jaws 54 and 55 have ends provided with holes through which passes a rod 59 projecting from a lug 60 extending upwardly from the fork 52. Surrounding the rod 50 59 and between the ends of the jaws 54 and 55 is a coil spring 61 tending to force together the lower ends of the jaws as allowed by the set screw 56. A coil spring 62 surrounds the rod 59 between the lug 60 and 55 the jaw 54 and tends to hold the jaws as a unit against the set screw 58. The picker fingers thus are normally held in fixed positions but they are held resiliently and capable of suiting themselves either separately and 60 individually or as a unit to the pieces and parts with which they co-act or engage.

The transfer carrier arm 36 swings in a plane which is a continuation of the plane of the chute 28 and the arm 51 is so mounted 65 and operated that it may extend the gripper fingers into the same plane. The transfer carrier arm receives the blanks in a substantially upright position and moves them to a substantially horizontal position. The cam 50 is so formed and timed as to cause the 70 picker fingers made up of the jaws 54 and 55 to descend upon and grasp the blank in the horizontal transfer carrier arm 36. The springs 61 and 62 give sufficiently to allow the fingers 54 and 55 or their forked tips to 75 separate and enter the openings through the bevels 45 and the sides of the cavity 46 in the carrier arm 36. See Figs. 8 and 9. The picker fingers now may grasp the blank and remove it from the carrier 36 as the cam 50 causes the arm 51 to rise. The picker fingers rise to allow the transfer carrier arm 36 to move past them toward its upright position and then the picker fingers move back and further downward past their former position so as to bring the blank about on the level with a stationary gripping jaw 63. The blank is maintained substantially horizontal 80 so long as it is held by the picker fingers.

Associated with the stationary jaw 63 is 85 the movable gripping jaw 64 carried by a block 65 sliding in transverse ways in the bed of the machine. In the same ways and beyond the block 65 is a second block 66. The block 65 is beveled at its rear end 65^a and is 90 provided with a cavity 67 into which telescopes an overlying tongue 68 extending from the block 66 the adjacent face of which is also beveled at 66^a and provided with a cavity 67^a into which telescopes an under- 95 lying tongue 68^a extending from the beveled face 65^a of the block 65. Between the beveled faces of the two blocks 65 and 66 and carried by the tongue 68 is an upwardly extending bolt 69 provided at its upper end with a nut 70 holding in place a washer 71 below which and surrounding the bolt 69 is a coil spring 72 which acts upon and normally forces downwardly a forked beveled wedge 73 mounted loosely on the bolt 69. The beveled forks of the wedge 73 straddle the tongues 68 and 68^a and engage the beveled faces 65^a and 66^a of the blocks 65 and 66. (See Figs. 6 and 7.) At its other end the block 66 is 100 forked and carries a transverse horizontal pin 74 on which is mounted a roller 75 within the fork which engages a cam 76 on the cam shaft 15 which as it turns normally forces the block 66 and the block 65 which 105 act as a unit because of the intermediate wedge 73 in the direction to cause the movable jaw 64 carried by the block 65 toward the stationary jaw 63 to grasp and hold the blank which has been brought to approximately the proper position by the picker fingers 54 and 55. The springs 61 and 62 at this time allow some freedom of movement of the picker fingers 54 and 55 to allow the blank to be properly and surely seated 110 in the jaws 63 and 64 so as to be securely 115 120 125 130

grasped and properly held by them. The cam 50 then allows the arm 51 to rise carrying with it the picker fingers 54 and 55 which because of their resilient mounting are 5 readily pulled from the blank which is now rigidly held between the jaws 63 and 64. An extension of the pin 74 in the block 66 carries a second roller 77 which is engaged by a cam 78 on the cam shaft 15 in such a way 10 that when the cam 78 acts on the roller 77 it retracts the movable jaw 64 to release the blank. If the blank is not properly positioned between the jaws 63 and 64 or if it is a defective blank or larger than the particular 15 jaws are set for or in any emergency the tapered wedge 73 may rise against the pressure of the spring 72 and allow the blocks 65 and 66 to telescope and avoid damage to the machine or any of its parts. As 20 shown in Fig. 5 the bolt 69 extends through the tongue 68 and into a cavity 69^a in the tongue 68^a of the block 65. This allows a limited freedom of movement but ensures the bolt 69 engaging the wall of the cavity 25 69^a to retract the jaw 64 when the cam 78 retracts the block 66.

The blocks 65 and 66 are held in their ways by caps 79 held on the bed of the machine by bolts. One of these bolts 80 may 30 be extended to support a vertical roller 81 above the cap 79. A vertical pivot pin 82 on the movable jaw 64 supports an angle lever one arm 83 of which engages the roller 82 as the movable jaw 64 is retracted from 35 the stationary jaw 63. (See Fig. 20.) This causes the other arm 84 of the angle lever to be moved away from the gripping face of the jaws. This arm 84 carries a transverse threaded plug 85 into which is 40 threaded a bolt 86 provided with a locking nut 87. The extreme end of the arm 84 is beveled at 88 to correspond with a beveled lug 89 held rigid on the stationary jaw 63. When the movable jaw approaches the 45 stationary jaw 63 the beveled end 88 engages the beveled lug 89 and causes the bolt 86 to approach the gripping face of the jaws. (See Fig. 19.) The blank is normally placed and held by the fingers 54 and 55 so 50 that its head is just within the protruding faces or shoulders of the jaws 63 and 64 and so that the shank of the blank will be grasped by the jaws immediately under the head. The bolt 86 may be properly adjusted 55 in the arm 84 and in the plug 85 so that in its final position it will engage the head of the blank and force it snugly against the shoulder of the gripping face of the jaws as shown in Fig. 19. As illustrated in 60 Fig. 24 the lower end of the chute 28 may be cut away or beveled and a shorter transfer carrier arm 36 employed so as to position the blanks in the picker fingers 54 and 55 so that the blanks will be placed adjacent 65 the gripping jaws 63 and 64 in such a way

that the blank heads will be gripped by the jaws and the entire shank protrude therefrom. By suitably adjusting the bolt 86 it may ensure a positioning of the blank to be gripped by the head so that the entire shank 70 of the blank may be free of the gripping jaws as indicated in Fig. 21. In this event the more or less circular opening in the gripping jaws adapted to the round shanks as illustrated in Fig. 22 may be replaced by 75 gripping jaws provided with a suitably formed rectangular opening illustrated in Fig. 23 and varying with the shape of the blank head. For operating on step bolt blanks angularly formed gripping jaws may 80 be employed to grasp the square of the shank.

The drive shaft 2 carries a long gear 90 which slidably engages a gear 91 on a reciprocating spindle 92 carried in an adjustable head 93 resting on the bed of the machine. Adjacent the gear 91 and surrounding the spindle is a coil spring 94 against which rests a collar 95 floating on the spindle, so that motion may be transmitted 90 through the spring from the collar 95 to the gear 91 and to the spindle 92. The collar 95 is provided with trunnion pins 95^a on which are trunnion blocks 95^b. The trunnion blocks 95^b slide in ways 96^a in a yoke 96 lever 96 on a shaft 97 which is mounted in transverse bearings in the head 93. An arm 98 extending rearwardly from the yoke 96 carries a roller 99 which may be engaged by a face cam 100 mounted on a drum 101 on the cam shaft 15. The cam 100 as it rotates forces the collar 95 as carried by the yoke 96 against the spring 94 in such a way as to reciprocate the spindle toward the blank gripping jaws 63 and 64. The roller 105 99 is later engaged by a cam 102 also carried by the drum 101 to force the collar 95 against a collar 102^a adjustable on the spindle 92 to positively retract the spindle. The trunnion collar 95 floats on the spindle between the spring 94 and the adjustable collar 102^a. The cams 100 and 102 are shown in detail in Fig. 15 and the cam 100 is shown 110 developed in Fig. 16.

The spindle carries at its end a cutter head 103 of any suitable well known type for cutting threads upon the blanks or for pointing bolts. In Fig. 21 is shown diagrammatically a bolt pointer head. The type illustrated in Figs. 1, 2 and 17 is a thread cutting die head 103 having a rear collar 104 pressure upon which will lock the cutters in their cutting position as is well known in the art. On a pin 105 (see Fig. 2) extending from the head and parallel with the spindle floats a yoke 106 which partially surrounds the spindle 92 just to the rear of the collar 104. A stop collar 107 is adjusted on the pin 105 so as to limit the float of the yoke 106. As the spindle is re- 125 130

ciprocated by the cam 102 it carries with it the yoke 106 which engages the stop 107 and puts upon the collar 104 sufficient pressure to close the cutters in the thread cutting die 5 head so that when the spindle in its return movement is pushed toward the blank the cutting head will operate on the blank.

The shaft 97 carries an arm 97^a adjustable along which is a weight 97^b. The tendency 10 of the weight is to force the arm 96 so as to keep the collar 95 against the stop collar 102^a on the spindle 92. This tends to keep the roller 99 snugly against the cam 100. When the thread cutting operation is completed 15 and the roller 99 rides off the cam 100 the weight 97^b tends to retract the spindle from the blank but the action may not be sure and strong enough to cause the yoke 106 to close the cutters in the thread cutting die head 103 and, therefore, the cam 102 may be employed to give a final and positive 20 retractive movement to the cutter head and so cause the cutters to close preparatory to the next forward movement caused by the cam 100.

The thread cutting die head illustrated is provided with the usual lug 108 projecting from its side, pressure upon which will open the cutters within the head. (See Fig. 17.) 30 A trip 109 is carried by a transverse block 110 resting in ways in the bed of the machine. The block 110 at its rear end carries a roller 111 which, as illustrated in Fig. 17, may be engaged by a cam 112 mounted on 35 the cam shaft 15. The stop is normally held retracted by a spring 119 in a pocket in the bed 1 and engaging a lug 119^a depending from the block 110. As the cam shaft rotates it forces the cam 112 against the 40 roller 111 and thus forces the stop 109 against the force of the spring 119 into position to be engaged by the lug 108 as the head rotates to open the cutters in the thread cutting die head. As shown in Fig. 1 the 45 trip 109 is long enough to operate on the lug 108 throughout its entire reciprocating movement so that it can open the cutters whenever forced forward by the cam 112. The cam 112 may be adjusted to operate 50 at any point in the stroke. By opening the thread cutting die head the thread cutting operation is discontinued and the amount of threads cut is limited irrespective of further reciprocation of the cutter 55 head toward the blank holding jaws. This also facilitates removal of the cutter head from the threaded blank.

When the cutting head 103 is a bolt pointer the stop 109 and its operating mechanism as well as the yoke 106 may be omitted or remain inoperative.

The jaws 63 and 64 hold the blank in axial alignment with the spindle 92 so that as the spindle reciprocates it causes the cutter head 103 to engage the shank of the

blank and point it or cut threads thereon. Any pitch of thread may be accommodated by varying the cams 100 and 102 so as to vary the speed and amplitude of the spindle reciprocations. Similarly the amount of 70 thread cut on the blank may be determined by a change in the gear ratio of the gears driving the cam shaft or by an adjustment of the cam 112 which brings into effect the stop 109 for opening the thread cutting die 75 head. The blank may be more conveniently grasped by its shank and its head brought snugly against the gripping jaws to aid in measuring with accuracy the amount of thread to be cut. When, however, it is desired to cut thread throughout the entire length of the shank of the blank it may be gripped by the head as shown in Fig. 21 and thus the entire shank may be exposed to the operation of the thread cutting die 80 head 103.

If the blank is not properly held to be engaged by the cutter head or if it is of unusual size or defective or any other contingency arise the spring 94 may contract 90 and save the cutter head from damage without interfering with the operation of the cams 100 and 102 and without stopping the movement of the collar 104. The amplitude of the throw of the lever arm 96 may be 95 less than the contraction of the spring 94 so that in emergencies the entire throw of the lever may be absorbed by compression of the spring 94 and the cutter head remain unmoved.

The spindle head 93 may be adjusted along the bed of the machine toward and from the holding jaws 63 and 64 to provide for operation upon blanks of different 100 lengths. A hand wheel 113 operating a gear 114 engaging a rack 115 in a well known way provides for movement of the spindle head. The usual bolts 116 are provided for holding the head in any of its adjustments. The gear 90 may be held on the driving shaft by a set screw 117 so that it may be adjusted along the driving shaft as the spindle head 93 is adjusted and thus the spindle may be rotated in whatever position the spindle head may be. Likewise 110 the drum 101 carrying the cams for operating the spindle may be adjusted along the cam shaft 15 and held by a set screw 118 so that the spindle may be properly reciprocated in any adjusted position the head 93 115 120 may take.

The spring 94 is stiff so that normally movement of the arm 96 will be transmitted to the spindle and the thread cutting die head will be brought into contact with the 125 blank and forced at least part way thereon. After the thread cutting operation has been started the thread cutting die head may be forced forward by the cam 100 or it may lead or draw itself onto the blank and 130

- continue forming threads thereon until the cutters are retracted or opened by the operation of the advanced stop 109 upon the cam 108. The throw of the cam 100, therefore, need not be as great in amplitude as the length of thread to be cut and the compression of the spring 94 may be always great enough to absorb the relative short throw of the cam 100.
- 10 It will be understood that in the normal operation of the machine a bolt blank dropped into the hopper 16 will be picked up by the chopper 17 and delivered to the chute 28. The blank will slide by gravity 15 against the locks 30 until the transfer carrier arm 36 approaches the chute and opens the locks 30 when the blank by its own weight will slide into the cavity 46 in the carrier. The arm 36 then moves through 20 substantially 60° so as to turn the blank from a substantially upright position to a substantially horizontal position in which position it is picked up by the picker fingers 54 and 55. The blank is then raised to allow the arm 36 to escape and then lowered to 25 a position adjacent the stationary gripper jaw 63 where it remains while the movable jaw 64 advances and grasps and holds the blank. While being gripped the blank is 30 properly positioned by the bolt 86. The fingers 54 and 55 are now withdrawn from the blank. While the blank is held in the jaws 63 and 64 the spindle advances and causes the cutter head 103 to act on the blank either 35 to point it or to cut threads on it. The stop 109 may then advance and open the cutter head, the spindle will be retracted and the movable jaw 64 will recede to release the blank which will fall out of the machine 40 and make place for another blank.
- I claim as my invention:
1. In a bolt threading machine, a drive shaft, a cam shaft driven thereby, a hopper for receiving bolt blanks, a chopper for arranging the blanks, a chute leading the blanks from the hopper, resilient locks at the outlet of the chute, a transfer arm opening the locks and releasing a single blank and receiving the released blank, means for causing the transfer arm to remove the blanks from the chute outlet, means for removing the blank from the transfer arm and placing it in position to be held, a pair of jaws for holding the blank, means for operating the jaws to grasp and release the blank, a spindle rotated from the drive shaft, a cutting head on the spindle, means for retracting the cutting head from the blank, means for closing the cutting head during its retracting movement, means for opening the cutting head after it has cut threads on the blank, means for actuating the opening means, and cams on the cam shaft for operating the transfer arm, the removing means, the jaw operating means, the cutting head opening actuating means and for reciprocating the spindle to cut threads on the blank.
- 45 2. In a bolt threading machine, a drive shaft, a cam shaft driven thereby, a hopper for receiving bolt blanks, a chute leading the blanks from the hopper, a lock at the outlet of the chute, a transfer arm receiving a blank from the chute, means for causing the transfer arm to remove the blank from the chute outlet, a pair of jaws for holding the blank, means for operating the jaws to grasp and release the blank, a spindle rotated from the drive shaft, a cutting head on the spindle, means for retracting the cutting head from the blank, means for closing the cutting head during its retracting movement, means for opening the cutting head after it has cut threads on the blank, means for actuating the opening means, and cams on the cam shaft for operating the transfer arm, the removing means, the jaw operating means, the cutting head opening actuating means and for reciprocating the spindle.
- 50 3. In a bolt threading machine, a drive shaft, a cam shaft driven thereby, a hopper for receiving bolt blanks, a chute leading the blanks from the hopper, a lock at the outlet of the chute, a transfer arm opening the locks and releasing a single blank and receiving the released blank, means for causing the transfer arm to remove the blanks from the chute outlet, a pair of jaws for holding the blank, means for operating the jaws to grasp and release the blank, a spindle rotated from the drive shaft, a cutting head on the spindle, means for retracting the cutting head from the blank, means for closing the cutting head during its retracting movement, means for opening the cutting head after it has cut threads on the blank, means for actuating the opening means, and cams on the cam shaft for operating the transfer arm, the removing means, the jaw operating means, the cutting head opening actuating means and for reciprocating the spindle.
- 55 4. In a bolt threading machine, a drive shaft, a cam shaft driven thereby, a hopper for receiving bolt blanks, a chute leading the blanks from the hopper, a lock at the outlet of the chute, a transfer arm opening the locks and releasing a single blank and receiving the released blank, means for causing the transfer arm to remove the blank from the chute outlet, a pair of jaws for holding the blank, means for operating the jaws to grasp and release the blank, a spindle rotated from the drive shaft, a cutting head on the spindle, means for reciprocating the spindle to cause the cutting head to operate on the blank, means for opening the cutting head after it has cut threads on the blank, means for actuating the opening means, and cams on the cam shaft for

operating the transfer arm, the removing means, the jaw operating means, the cutting head opening actuating means and the spindle reciprocating means.

5 2. In a bolt threading machine, a drive shaft, a cam shaft driven thereby, a hopper for receiving bolt blanks, a chute leading the blanks from the hopper, a lock at the outlet of the chute, a transfer arm receiving a blank from the chute, means for causing the transfer arm to remove the blank from the chute outlet, means for removing the blank from the transfer arm and placing it in position to be held, a pair of jaws for holding the blank, means for operating the jaws to grasp and release the blank, a spindle rotated from the drive shaft, a cutting head on the spindle, means for retracting the cutting head from the blank, means for closing the cutting head during its retracting movement, means for opening the cutting head after it has cut threads on the blank, means for actuating the opening means, and cams on the shaft for operating the transfer arm, the removing means, the jaw operating means, the cutting head opening actuating means and for reciprocating the spindle to cut threads on the blank.

10 3. In a bolt threading machine, a drive shaft, a cam shaft driven thereby, a hopper for receiving bolt blanks, a chute leading the blanks from the hopper, a lock at the outlet of the chute, a transfer arm opening the locks and releasing a single blank and receiving the released blank from the chute, means for causing the transfer arm to remove the blank from the chute outlet, a pair of jaws for grasping and holding the blank, means for operating the jaws to grasp and release the blank, a spindle rotated from the drive shaft, a cutting head on the spindle, means for retracting the cutting head from the blank, means for closing the cutting head during its retracting movement, means for opening the cutting head after it has cut threads on the blank, means for actuating the opening means, and cams on the cam shaft for operating the transfer arm, the removing means, the jaw operating means, the cutting head opening actuating means and for reciprocating the spindle.

15 4. In a bolt threading machine, a drive shaft, a cam shaft driven thereby, a hopper for receiving bolt blanks, a chute leading the blanks from the hopper, a lock at the outlet of the chute, a transfer arm opening the locks and releasing a single blank and receiving the released blank, means for causing the transfer arm to remove the blank from the chute outlet, a pair of jaws for holding the blank, means for operating the jaws to grasp and release the blank, a spindle rotated from the drive shaft, a cutting head on the spindle, means for reciprocating the spindle to cause the cutting head to operate on the blank, means for opening the cutting head after it has cut threads on the blank, means for actuating the opening means, and cams on the cam shaft for

cating the spindle from the blank, means for closing the cutting head during its re-tacting movement, means for opening the cutting head after it has cut threads on the 5 blank, and means for actuating the opening means.

5. Means for holding a blank comprising a stationary jaw member, a movable jaw member, a block reciprocating in guide ways 10 and carrying the movable jaw member at one end, a beveled surface at the other end of the block, a tapered wedge engaging the beveled surface, a second block having a beveled surface engaging the tapered wedge, 15 a spring carried by the second block pressing the wedge between the blocks, a roller on the second block, and a cam engaging the roller to normally cause the blocks to reciprocate to operate the jaws.

20 6. Means for holding a blank comprising a stationary jaw member, a movable jaw member, a block reciprocating in guide ways and carrying the movable jaw member at one end, a second block, a tapered wedge, a 25 spring carried by the second block pressing the wedge between the blocks, and means engaging the second block to cause the blocks to reciprocate to operate the jaws.

7. Means for holding a blank comprising a 30 stationary jaw member, a movable jaw member, a block reciprocating in guide ways and carrying the movable jaw member at one end, a beveled surface at the other end of the block, a tapered wedge engaging the beveled 35 surface, a second block having a beveled surface engaging the tapered wedge, a spring carried by the second block pressing the wedge between the blocks, and means engaging the second block to operate the jaws.

40 8. Means for holding a blank comprising a jaw member, a second jaw member movable relatively thereto, a block carrying the movable jaw member, a second block, a tapered wedge between and engaging both blocks, a 45 spring carried by the second block pressing the wedge between the blocks, a roller on the second block, and a cam engaging the roller to normally cause the blocks to reciprocate to operate the jaws.

50 9. Means for holding a blank comprising a stationary jaw member, a movable jaw member, an arm pivotally mounted on the movable jaw member, an aligning block carried by the arm, a block on the stationary jaw member engaging the arm when the jaws close, and a stationary roller engaging the arm when the jaws open.

55 10. Means for holding a blank comprising a stationary jaw member, a movable jaw member, an arm pivotally mounted on the movable jaw member, an adjustable aligning block carried by the arm, a block on the stationary jaw member engaging the arm when the jaws close, and a stationary roller 60 engaging the arm when the jaws open.

11. Means for holding a blank comprising a stationary jaw member, a movable jaw member, an arm pivotally mounted on the movable jaw member and having one end beveled, an aligning block carried by the 70 arm, a beveled block on the stationary jaw member engaging the arm when the jaws close, and a stationary roller on the machine engaging the arm when the jaws open.

12. Means for holding a blank comprising a stationary jaw member, a movable jaw member, an angle lever pivotally mounted on the movable jaw member, an aligning block carried by one arm of the lever, a block on the stationary jaw member engaging the said 75 arm when the jaws close, and a stationary roller on the machine engaging the other arm of the angle lever when the jaws open.

13. In a machine of the character described, the combination with a movable 80 gripping jaw, of means carried by the jaw but movable with respect thereto for aligning headed blanks therein comprising a finger for positively holding the heads against the jaws.

14. In combination, a movable gripping jaw, a finger carried by the jaw for aligning blanks therein, means for moving the jaw and finger, and means for moving the finger with respect to the jaw.

15. In a machine of the character described, a blank supporting track, a resilient lock at the delivery end of the track, a carrier movable from a substantially horizontal to a substantially vertical position and vice 100 versa toward and from the delivery end of the track, means on the carrier to open the lock, reciprocatory fingers, and mechanism for moving the fingers to and from, and then down past the carrier.

16. In a machine of the character described, a blank supporting track, a resilient lock at the delivery end of the track, a carrier movable from a substantially horizontal to a substantially vertical position and vice 110 versa toward and from the delivery end of the track, and means on the carrier to open the lock.

17. In a machine of the character described, a blank supporting track, a resilient lock at the delivery end of the track, a carrier movable from a substantially horizontal to a substantially vertical position and vice 115 versa toward and from the delivery end of the track, means on the carrier to open the lock, resiliently mounted reciprocatory fingers, and mechanism for moving the fingers to and from, and then down past the carrier.

18. In a blank feeding mechanism including a runway for blanks, a resilient lock at the delivery end of the runway, a carrier movably mounted to receive blanks delivered by natural forces thereto in a substantially upright position from said runway and to 125 130

carry them to a substantially horizontal position; and means for lifting said blanks from said carrier and for bodily conveying them to a position to be grasped and held.

19. In a blank feeding mechanism including a runway for blanks, a resilient lock at the delivery end of the runway, and a carrier movably mounted to receive blanks delivered by natural forces thereto in a substantially upright position from said runway and to carry them to a substantially horizontal position.

20. In a blank feeding mechanism including a runway for blanks, a resilient lock at the delivery end of the runway, a carrier movably mounted to receive blanks delivered by natural forces thereto in a substantially upright position from said runway and to carry them to a substantially horizontal position, means carried by said carrier to open said lock, and means for lifting said blanks from said carrier and for bodily conveying them to a position to be grasped and held.

21. In a blank feeding mechanism including a runway for blanks, a resilient lock at the delivery end of the runway, a carrier movably mounted to receive blanks delivered by natural forces thereto in a substantially upright position from said runway and to carry them to a substantially horizontal position, and means carried by said carrier to open said lock.

22. Means for operating movable cutter heads including a longitudinally moving spindle, a cutter head thereon, a transversely moving stop, means to move the stop toward the spindle at a predetermined point in the spindle movement, and means on the cutter head engaged by the stop to open the cutter head.

23. Means for operating movable cutter heads including a longitudinally moving spindle, a cutter head thereon, means adjacent the spindle to close the cutter head, a transversely moving stop, and means on the cutter head engaged by the stop to open the cutter head.

24. Means for operating movable cutter heads including a longitudinally moving spindle, a cutter head thereon, a transversely moving stop, and means on the cutter head engaged by the stop to open the cutter head at a predetermined point in its movement.

25. Means for operating movable cutter heads including a longitudinally moving spindle, a cutter head thereon, means to close the cutter head toward the end of its movement in one direction, a transversely moving stop, and means on the cutter head engaged by the stop to open the cutter head toward the end of its movement in the other direction.

26. Means for operating movable cutter heads including a longitudinally moving

cutter head, a stationary shaft, a stop on the shaft, and a yoke floating on the shaft and extending into the path of the head and adapted to close the cutter head when the yoke engages the stop.

27. An adjustable head stock, a longitudinally moving cutter head in the head stock, a stationary shaft in the head stock, a stop on the shaft, and a yoke floating on the shaft and extending into the path of the cutter head and adapted to close the cutter head when the yoke engages the stop.

28. Means for operating movable cutter heads including a longitudinally moving spindle, a cutter head thereon, a transversely moving stop, means on the cutter head engaged by the stop to open the cutter head, a stationary shaft, a stop on the shaft, and a yoke floating on the shaft and extending into the path of the cutter head and adapted to close the cutter head when the yoke engages the last mentioned stop.

29. Means for operating movable cutter heads including a cutter head movable toward and away from a blank, a stationary shaft, a stop on the shaft, and a yoke floating on the shaft and extending into the path of the head and adapted to close the cutter head when the yoke engages the stop in its travel away from the blank.

30. Blank handling and transferring mechanism comprising an arm, a fork at one end thereof, a pair of pick up fingers pivoted together in the fork intermediate their ends, a set screw in one finger bearing against the other finger between the pivot and the gripping end of the fingers, a set screw in the fork and bearing against the adjacent finger, a guide rod extending from the fork through the non-gripping ends of the fingers, a spring on the rod between the fingers, a spring on the rod between the fork and the adjacent finger, and means for swinging the arm to move the fingers through an arc.

31. Blank handling and transferring mechanism comprising an arm, a fork at one end thereof, a pair of pick up fingers pivoted together in the fork intermediate their ends, a guide rod extending from the fork through the non-gripping ends of the fingers, a spring on the rod between the fingers, a spring on the rod between the fork and the adjacent finger, and means for swinging the arm to move the fingers through an arc.

32. Blank handling and transferring mechanism comprising an arm, a pair of pick up fingers pivoted together on the arm intermediate their ends, a set screw in one finger bearing against the other finger between the pivot and the gripping end of the fingers, a set screw on the arm and bearing against the adjacent finger, and resilient means for forcing the gripping ends of the fingers toward each other.

33. Blank handling and transferring

- mechanism comprising an arm, a pair of pick up fingers pivoted together on the arm intermediate their ends, a set screw in one finger bearing against the other finger between the pivot and the gripping end of the fingers, a set screw on the arm and bearing against the adjacent finger, a guide rod extending from the arm through the non-gripping ends of the fingers, a spring on the rod between the fingers, a spring on the rod between the arm and the adjacent finger, and means for swinging the arm to move the fingers through an arc.
34. Blank handling and transferring mechanism comprising an arm, a pair of pick up fingers resiliently pivoted together on the arm intermediate their ends, a set screw in one finger bearing against the other finger between the pivot and the gripping end of the fingers, and a set screw on the arm and bearing against the adjacent finger.
35. Blank handling and transferring mechanism comprising an arm, a pair of pick up fingers pivoted together on the arm intermediate their ends, a guide rod extending from the arm through the non-gripping ends of the fingers, a spring on the rod between the fingers, a spring on the rod between the arm and the adjacent finger, and means for swinging the arm to move the fingers through an arc.
36. An arm, pick up fingers pivoted together on the arm, resilient means for holding the fingers in position on the arm, and resilient means for holding the fingers in position with relation to each other.
37. Blank handling mechanism comprising a hopper for blanks, an arm for receiving blanks from the hopper inclined 30° to the perpendicular, a shaft carrying the arm, a pinion on the shaft, an arc arm pivoted intermediate its ends, a toothed arc on one end of the arc arm engaging the pinion, a cam shaft, and a cam on the shaft to cause the receiving arm to travel 60° to a horizontal position and vice versa.
38. Blank handling mechanism comprising a hopper for blanks, an arm for receiving blanks from the hopper inclined 30° to the perpendicular, a shaft carrying the arm, a pinion on the shaft, an arc arm pivoted intermediate its ends, a toothed arc on one end of the arc arm engaging the pinion, a cam shaft, a cam on the cam shaft to cause the receiving arm to travel 60° to a horizontal position and vice versa, and picker fingers to remove the horizontal blank from the receiving arm and place it in position to be held horizontally.
39. Blank handling mechanism comprising a hopper for blanks, an arm for receiving blanks from the hopper inclined 30° to the perpendicular, a shaft carrying the arm, a pinion on the shaft, a pivoted arc arm, a toothed arc on the arc arm en-
- gaging the pinion, a cam to cause the receiving arm to travel 60° to a horizontal position and vice versa.
40. Blank handling mechanism comprising a hopper for blanks, an arm for receiving blanks from the hopper inclined 30° to the perpendicular, a shaft carrying the arm, a pinion on the shaft, a pivoted arc arm, a toothed arc on the arc arm en-
- gaging the pinion, a cam to cause the receiving arm to travel 60° to a horizontal position and vice versa, and picker fingers to remove the horizontal blank from the receiving arm and place it in position to be held horizontally.
41. Blank handling mechanism comprising a hopper for blanks, an arm for receiving blanks from the hopper in a substantially perpendicular position, a shaft carrying the arm, a pinion on the shaft, an arc arm, a toothed arc on the arc arm engaging the pinion, a cam to cause the receiving arm to travel to a substantially horizontal position and vice versa.
42. Blank handling mechanism comprising a hopper for blanks, an arm for receiving blanks from the hopper in a substantially perpendicular position, a shaft carrying the arm, a pinion on the shaft, an arc arm, a toothed arc on the arc arm en-
- gaging the pinion, a cam to cause the receiving arm to travel to a substantially horizontal position and vice versa, and picker fingers to remove the horizontal blank from the receiving arm and place it in position to be held horizontally.
43. Blank handling mechanism comprising a hopper for blanks, an arm for receiving blanks from the hopper inclined 30° to the perpendicular, a shaft carrying the arm, and a cam to cause the receiving arm to travel 60° to a horizontal position and vice versa.
44. Blank handling mechanism comprising a hopper for blanks, an arm for receiving blanks from the hopper inclined 30° to the perpendicular, a shaft carrying the arm, a cam to cause the receiving arm to travel 60° to a horizontal position and vice versa, picker fingers for removing the horizontal blank from the receiving arm, and gripping jaws for gripping the blank while held by the fingers and holding it horizontal.
45. Bolt threading mechanism comprising a bed, a blank holder stationary on the bed, a head adjustable toward and from the blank holder, a spindle in the head, a cutting head on the spindle, a gear on the spindle, a drive shaft on the bed, a gear adjustable along the drive shaft to engage the gear on the spindle and rotate the spindle, a cam shaft on the bed and driven from the drive shaft, means carried by the adjustable head to reciprocate the spindle in the

head toward and from the blank holder, and a cam adjustable on the cam shaft to operate the spindle reciprocating means.

46. Bolt threading mechanism comprising a bed, a blank holder stationary on the bed, a head adjustable toward and from the blank holder, a spindle in the head, a cutting head on the spindle, a gear on the spindle, a drive shaft on the bed, a gear adjustable along the drive shaft to engage the gear on the spindle and rotate the spindle, a cam shaft on the bed and driven from the drive shaft, means carried by the adjustable head to reciprocate the spindle in the head toward and from the blank holder, a cam adjustable on the cam shaft to operate the spindle reciprocating means, and means to hold the adjustable parts in their adjusted positions.

20 47. Bolt threading mechanism comprising a bed, a blank holder stationary on the bed, a head adjustable toward and from the blank holder, a spindle in the head, a cutting head on the spindle, a gear on the spindle, a drive shaft on the bed, a gear adjustable along the drive shaft as the head is adjusted and arranged to slidably engage the gear on the spindle and rotate the spindle, a cam shaft on the bed and driven from the drive shaft, means carried by the adjustable head to reciprocate the spindle in the head toward and from the blank holder, and a cam adjustable on the cam shaft as the head is adjusted and arranged to operate the spindle reciprocating means.

48. Bolt threading mechanism comprising a bed, a blank holder stationary on the bed, a head adjustable toward and from the blank holder, a spindle in the head, a cutting head on the spindle, a gear on the spindle, a drive shaft on the bed, a gear adjustable along the drive shaft as the head is adjusted and arranged to slidably engage the gear on the spindle and rotate the spindle, a cam shaft on the bed and driven from the drive shaft, means carried by the adjustable head to reciprocate the spindle in the head toward and from the blank holder, a cam adjustable on the cam shaft as the head is adjusted and arranged to operate the spindle reciprocating means, and means to hold the adjustable parts in their adjusted positions.

49. Bolt threading mechanism comprising a bed, a blank holder stationary on the bed, a head adjustable toward and from the blank holder, a spindle in the head, a cutting head on the spindle, a gear on the spindle, a drive shaft on the bed, a gear adjustable along the drive shaft to engage the gear on the spindle throughout its reciprocation and rotate the spindle, a cam shaft on the bed and driven from the drive shaft, means carried by the adjustable head to reciprocate the spindle in the head toward

and from the blank holder, and a cam adjustable on the cam shaft to operate the spindle reciprocating means.

50. Bolt threading mechanism comprising a bed, a blank holder stationary on the bed, a head adjustable toward and from the blank holder, a spindle in the head, a cutting head on the spindle, a gear on the spindle, a drive shaft on the bed, a gear adjustable along the drive shaft to engage the gear on the spindle throughout its reciprocation and rotate the spindle, a cam shaft on the bed and driven from the drive shaft, means carried by the adjustable head to reciprocate the spindle in the head toward and from the blank holder, a cam adjustable on the cam shaft to operate the spindle reciprocating means, and means to hold the adjustable parts in their adjusted positions.

51. Bolt threading mechanism comprising a bed, a blank holder stationary on the bed, a head adjustable toward and from the blank holder, a spindle in the head, a cutting head on the spindle, a gear on the spindle, a drive shaft on the bed, a gear adjustable along the drive shaft to engage the gear on the spindle and rotate the spindle, and means carried by the adjustable head to reciprocate the spindle in the head toward and from the blank holder.

52. Bolt threading mechanism comprising a bed, a blank holder stationary on the bed, a head adjustable toward and from the blank holder, a spindle in the head, a cutting head on the spindle, a gear on the spindle, a drive shaft on the bed, a gear adjustable along the drive shaft to engage the gear on the spindle and rotate the spindle, means carried by the adjustable head to reciprocate the spindle in the head toward and from the blank holder, and means to hold the adjustable parts in their adjusted positions.

53. Feeding mechanism for bolt threading machines comprising a spindle, an arm for reciprocating the spindle having a yielding contact with the spindle in one direction and a solid contact in the other direction, and a weighted arm tending to throw the reciprocating arm against the solid contact.

54. Feeding mechanism for bolt threading machines comprising a spindle, a spring thereon, a fixed collar on the spindle, a floating collar between the spring and collar, an arm for moving the floating collar to reciprocate the spindle, and a weight tending to keep the arm in position to force the floating collar against the fixed collar.

55. Feeding mechanism for bolt threading machines comprising a spindle, a thread cutting die head on the spindle, a removable cam to reciprocate the spindle to cut threads

- on a blank so arranged that a variation in the cam may change the pitch of the thread cut on the blank. 40
56. Feeding mechanism for bolt threading machines comprising a blank holder, a reciprocating spindle, a lever for reciprocating the spindle, and a compression spring between the lever and spindle having sufficient compression to take up the entire 10 throw of the lever. 45
57. Feeding mechanism for bolt threading machines comprising a spindle, a spring surrounding the spindle, a trunnion collar loose on the spindle and engaging the 15 spring, trunnion pins on the collar, trunnion blocks on the pins, a pivoted lever arm, ways on the lever arm in which the trunnion blocks slide, and means for swinging the lever arm to reciprocate the spindle 20 through the spring. 50
58. Feeding mechanism for bolt threading machines comprising a spindle, a thread cutting die head on the spindle, a cam shaft, cams thereon, mechanism operated by the 25 cams to reciprocate the spindle, and gearing through which the drive shaft drives the cam shaft so arranged that a change in the gear ratio will change the amount of thread cut on a blank. 55
59. Feeding mechanism for bolt threading machines comprising a spindle, a spring thereon, a fixed collar on the spindle, a floating collar between the spring and fixed collar, an arm for moving the floating collar 30 to reciprocate the spindle, a weight tending to keep the arm in position to force the floating collar against the fixed collar, a 35 cam for throwing the arm against the spring, and a cam for throwing the arm against the fixed collar. 60
60. Feeding mechanism for bolt threading machines comprising a spindle, a spring thereon, an adjustable collar on the spindle, a floating collar between the spring and adjustable collar, an arm for moving the floating collar to reciprocate the spindle, and a weight tending to keep the arm in position to force the floating collar against the adjustable collar. 65
61. Feeding mechanism for bolt threading machines comprising a spindle, a cutter head thereon, a lever arm to thrust it resiliently toward a blank, a weight acting to retract the spindle, a cutter head closing device in the path of the head during retraction, a cam causing the lever arm to force the spindle toward the blank, and a cam causing the lever arm to force the cutter head positively against the closing device. 70
62. A spindle, a cam, resilient means acted on by the cam to force the spindle in one direction, a weight, and rigid means acted on by the weight to force the spindle in the opposite direction. 75
63. A spindle, a cam, resilient means acted on by the cam to force the spindle in one direction, a weight, rigid means acted on by the weight to force the spindle in the opposite direction, and a second cam acting on the rigid means to force the spindle in the same direction as the weight. 80

MICHAEL J. RILEY.
